VEHICLE DOOR LATCH

Holden W. Rightmyer, Toledo, Ohio, assignor to
 The American Swiss Company, Toledo, Ohio,
 a corporation of Ohio

Application December 21, 1936, Serial No. 116,924

5 Claims. (Cl. 292—169)

This invention relates to door latches for vehicles and particularly to latches for the decks of automobiles and an object is to produce a new and improved latch of this character, the operating handle of which can be rendered operative by manipulating a dogging member which may form part of a key controlled mechanism, the dogging member being held in retracted position until the latch bolt is again retracted, whereupon the handle is automatically dogged. This is particularly useful in connection with the deck lids or compartment doors of automobiles, because it enables the door or lid to be unlocked by means of a key and then the key removed. The door will remain unlocked until the door is slammed to closed position, whereupon it is automatically locked. Although the invention is particularly useful in connection with deck lids, it can be used to advantage elsewhere, and it is not intended that the invention be so restricted.

Other objects and advantages of the invention will hereinafter appear and for purposes of illustration but not of limitation, embodiments of the invention are shown on the accompanying drawings, in which

Figure 1 is a top plan view of the door latch mechanism embodying the invention;

Fig. 2 is a side edge view of the parts shown in Fig. 1;

Fig. 3 is a front edge view of the latch mechanism;

Figure 3A is a fragmentary plan view of the latch with the cover plate removed;

Fig. 4 is a top plan view of an alternate form of latch mechanism;

Fig. 5 is a front edge view of the latch shown in Fig. 4, and

Fig. 6 is a side edge elevation of the latch shown in Fig. 4.

The illustrated embodiment of the invention shown in Figures 1 to 3 comprises a door latch having a case plate 10 provided with a flange 11 at one end which is apertured to receive a bolt nose 12. The bolt nose 12 is secured by rivets 13 to a bolt plate 14 which is movable longitudinally along the case plate 10. Formed in the front end of the bolt plate 14 is a horizontal slot 15 through which the handle shaft (not shown) is adapted to extend, the latter being square in cross section and fitting a similarly shaped opening 16 in a roll back 17 suitably mounted on the case plate 10. The roll back 17 has oppositely disposed arms 18 which engage with shoulders 19 provided on the bolt plate 14. It will be obvious that the

latch bolt is retracted upon turning of the roll back 17 in one direction or the other.

The bolt nose 12 is normally urged to latching position by means of a coil spring 20 disposed in a slot 21 formed in the bolt plate 14. The rear end of the spring bears against the downwardly extending tongue 22 integral with the cover plate 30 and the forward end of the spring bears against a tongue 23 which depends from the bolt plate 14 in the forward end of the slot 21. It will be apparent that the spring 20 normally holds the shoulders 19 against the arms 18 of the roll back.

Disposed on the upper side of the bolt plate 14 is a dogging slide 24 on one side of which is a rod 25, about which is disposed a coil spring 26 which bears at one end against the slide 24 and at the other end against a bracket 27 mounted on the case plate 10. The spring 25 normally urges the dogging slide 24 toward the roll back 17. In the front end of the dogging slide 24 is formed a notch 28 which is adapted, when the slide 24 is in its forward position, to engage the squared handle shaft (not shown) in the roll back opening 16, thereby to prevent turning movement of the handle shaft and roll back 17. At the rear end of the dogging slide 24 is a downturned flange 29 which is adapted to ride on the case plate 10. Fitting over the dogging slide 24 and a portion of the bolt plate 14 is a cover plate 30 having a plurality of ears 31 which extend through openings in the case plate 10 and are bent over against the under side thereof, to hold the cover plate in position.

The dogging slide 24 is retracted by a shaft, (not shown), engaging in an opening 32, such shaft extends outwardly through a cylinder lock housing 33, the cylinder lock being omitted from the drawings. The opening 32 is formed in an eccentric cam 34. Formed in the dogging slide 24 is an opening 35 and against the rear edge of this opening, the eccentric cam 34 is held by the coil spring 26. It will be apparent that by turning movement of the cam 34, the dogging slide 24 is retracted against the force of the spring 26 to permit the squared handle shaft disposed in the opening 16 to be freed and thereby permit retraction of the latch bolt.

In accordance with this invention, the dogging slide 24 is retained in its retracted position until further retraction of the latch bolt. For this purpose a detent 36 is pivoted at 37 to the case plate 10 and is urged in a counter-clockwise direction (Fig. 1) by a spring 38. One end portion 39 of the detent 36 is adapted to engage the flange 29 at the rear of the dogging slide 24. It

will be apparent that when the dogging slide 24 has been retracted sufficiently to free the roll back 17, the end portion 39 of the detent 36 will be snapped into blocking position as shown in Fig. 1, preventing movement of the dogging slide 24 to the left of the figure. Forming a part of the detent 36 is a lateral extension 40 which is disposed, when the detent is in operative or slide engaging position, in the rear of a flange 10 or shoulder 41 of the bolt plate 14. It will be apparent that upon retraction of the bolt as by slamming of the door, the shoulder 41 will abut against the extension 40 and swing the detent 36 to the right or in a clockwise direction so that 15 the end portion 39 is moved away from the shoulder 29, thereby permitting the spring 26 to move the dogging slide 24 to the left of the figure or into operative or dogging position.

It will be apparent that a cylinder lock mechanism is disposed within the tubular housing 33, and may be held in place by a set screw 42. Since such mechanism is well-known to those skilled in this art, description thereof is not considered necessary. It will be understood, however, that 25 the shaft fitting the squared opening 32 may be turned by means of a key fitting such cylinder lock from the outside of the door so that upon turning the key the dogging slide 24 is retracted and thereupon turning of the handle shaft which 30 fits the opening 16, the bolt nose 12 may be retracted sufficiently to enable the door to be opened.

The form shown in Figures 4 to 6 is similar to that above described but in this form the roll back 17a has a slot 43 which is adapted to receive an extension 44 on the dogging slide 24a. It is apparent that in this form, the roll back itself is engaged or dogged instead of the handle shaft as in the form shown in Figures 1 to 3.

40 In this form, the dogging slide 24a is formed with a cutout portion providing a shoulder 29a which is engaged by the end of the pivoted detent 36a when the dogging slide 24a is retracted sufficiently. To provide for slam unlocking or 45 releasing of the detent 36a when the latch bolt 12a is retracted, a flange 45 is formed on the detent. When in dogging position, the flange 45 is disposed substantially in engagement with a cam shoulder 41a of the bolt plate. Upon retraction of the latch bolt, the cam 41a is moved 50 rearwardly into engagement with the flange 45 thereby swinging the detent 36a upwardly against the force of the spring 38a and allowing the dogging slide 24a to be moved forwardly by means 55 of a spiral spring 26a, one end of which is anchored to the case plate 10a and the opposite end of which engages a bolt on the dogging slide. A spiral spring 20a is provided for holding the latch bolt 12a normally in latching position. The 60 dogging slide 24a is similarly retracted by an eccentric cam 34a in a similar manner to the eccentric cam 34 above described, so that further description of the operation and mechanism of this form is not considered necessary.

65 It will be understood that numerous changes in details of construction, arrangement and operation may be effected without departing from the spirit of the invention, especially as defined in the appended claims.

What I claim is:

1. A vehicle door latch comprising a spring tensioned latch bolt movable to and from latching position, a retractor for moving said bolt away from latching position, a dog for holding said retractor against operative movement, manual means for moving said dog to inoperative position enabling operative movement of said retractor, a detent separate from said dog and engageable with said dog for retaining same in inoperative position, spring means urging said detent into dog-engaging position, and means operable automatically to release said detent upon retraction of said bolt. 5

2. A vehicle door latch comprising a spring 15 tensioned latch bolt movable to and from latching position, a retractor for moving said bolt away from latching position, a dog for holding said retractor against operative movement, spring means urging said dog toward said retractor, 20 manual means for moving said dog to inoperative position enabling operative movement of said retractor, a detent engageable with said dog for retaining same in inoperative position, spring means normally urging the detent into dog-engaging position, and means operable automatically to release said detent upon retraction of said bolt, whereby said dog abruptly returns to retractor-blocking position. 25

3. A vehicle door latch comprising a spring 30 tensioned latch bolt movable to and from latching position, a retractor for moving said bolt away from latching position, a dogging slide spring urged to engage said retractor to block operative movement thereof, manual means for 35 positively retracting said slide away from said retractor to enable operation thereof, a detent automatically engageable with said slide for retaining same in retracted position, and bolt-actuated means for releasing said detent upon 40 retraction of said bolt.

4. A vehicle door latch comprising a spring tensioned latch bolt movable to and from latching position, a retractor for moving said bolt away from latching position, a dogging slide 45 spring urged to engage said retractor to block operative movement thereof, manual means for moving said slide away from said retractor, a spring tensioned pivoted detent engageable with said slide upon retraction thereof to retain same in inoperative position, and means on the bolt 50 for rocking said detent out of slide-engaging position for releasing the slide upon retraction of said bolt.

5. A vehicle door latch comprising a spring 55 tensioned latch bolt movable to and from latching position, a retractor for moving said bolt away from latching position, a dogging slide spring urged to engage said retractor to block operative movement thereof, manual means for 60 moving said slide away from said retractor, a spring tensioned pivoted detent engageable with said slide upon retraction thereof to retain same in inoperative position, and a cam on said bolt for rocking said detent away from said slide upon 65 retracting movement of the bolt.

HOLDEN W. RIGHTMYER.
